UNITED STATES PATENT OFFICE.

MICHAEL J. TRACY, OF ST. LOUIS, MISSOURI.

LATCH.

Application filed April 23, 1928. Serial No. 271,991.

This invention relates to latches.

An object of the invention is to provide an improved latch for use in locking sliding doors and comprising a longitudinally movable latching element supported by the wall structure instead of the door and arranged to engage with parts at the upper and lower ends of the door to hold the door closed and being capable of longitudinal movement to disengage said parts to permit movement of the door.

Another object of the invention is to provide means for selectively disengaging a number of said latching elements so that one or more doors may be opened, as desired.

Another object of the invention is to provide an improved latch possessing the advantages and merits of the latch herein disclosed, reference being made to the drawing in which

Fig. 1 is a front elevation of a structure comprising a door having my improved latch cooperative therewith.

Fig. 2 is a horizontal sectional view approximately on the line 2—2 of Fig. 1.

Fig. 3 is an enlarged vertical sectional view approximately on the line 3—3 of Fig. 1.

Fig. 4 is an enlarged horizontal sectional view of adjacent portions of the wall and door structures showing the latching element in connection therewith.

Fig. 5 is a vertical sectional view of the construction shown in Fig. 4, approximately on the line 5—5 of Fig. 4.

For convenience of illustration I have shown my invention satisfactorily embodied in a structure comprising a barred wall 1 having a door opening 2 and a laterally slideable barred door 3 for said opening. The upper end of the door has a hanger bracket 4 in connection therewith extending into a housing 5 and seating upon a series of balls 6 into a support 7. The door is thus supported for lateral sliding movements to and from closed position.

Near one side of the door opening 2 a vertical tube 8 is secured rigidly in and as a part of the wall 1 and has its upper end opening into the enclosure 5 (Fig. 3). The bracket 4 comprises a wide lateral portion 9 having a longitudinal slot 10 of less diameter than the diameter of the lock bar 11. The lock bar 11 is mounted for vertical movement within the tube 8 and projects upwardly into the enclosure 5 through the slot 10 and in its lower position, which is its latching position, engages in notches in the bracket 9 at the sides

of the slot 10, thus positively latching the door 3 in closed position.

The lower end of the door has a bar 12 rigid therewith extending under the lower frame member 13 which extends across the lower end of the door opening and laterally for connection with the lower ends of the bars of the wall 1. To the lower side of the frame member 13 a channel 14 is rigidly secured and the lower side of the bar 12 is formed with a groove 15 which rides the upper edge of the outer wall of the channel 14 (Fig. 5). In its lower position the lower end of the latch bar 11 projects through the frame member 13 and engages in a notch 16 in the bar 12, thus latching the lower end of the door.

A plate 17 is rigidly attached to the upper end of each latch bar 11 and operates between guide brackets 18 within the enclosure 5. A notch 19 is formed in the inner edge of the plate 17 and a longitudinally movable bar 20 extends through the notches 19 of all of the plates 17. The plate 17 has a roller 21 extending over the bar 20 and arranged to be engaged by a cam 22 on the bar 20 when said bar 20 is moved in one direction from a starting position. Thus, the corresponding locking bar 11 may be raised to disengage the lower end thereof from the bar 12 and to position the notches 23 within the slot 10 so as to release the bracket extension 9 and permit the door to be moved laterally from closed position. The cam 22 also extends below the lower edge of the bar 20 and in the starting position of said bar 20 is within the notch 19 so as to prevent movement of the bar 11 to released position. The lower ends of the cam 22 are out of vertical alinement with the high point of the upper end of said cam so that movement of the latch bar 11 by the upper and lower high points of the cam is possible. Another cam 24 is secured to the bar 20 for each latch bar 11. Thus, where there is a series of doors 3, any number or selected ones of said doors may be released by positioning the cams 22 and 24 in proper relationship upon the bar 20 so that movement of said bar 20 longitudinally to different positions will raise selected ones of the bars 11 to released positions.

An angular arm 25 has one end pivoted to the door 3 (Fig. 1) and the opposite end extending through a hole in the plate 17 bearing upon a roller 26 supported by said plate 17. Thus, when the bar 11 is raised the free end of the arm 25 is raised. A projection 27

is attached to the free end of the arm 25 and is adapted to be engaged in a notch 28 in a longitudinally movable operating bar 29.

To open any number or selected ones of a plurality of doors 3 the index cam bar 20 is moved longitudinally so as to cause the properly positioned cams 22 and 24 to move the corresponding latch bars 11 vertically to disengage the lower ends of such selected locking bars from the bars 20 of the corresponding doors and to place the notches 22 within the slot 10. As before stated, when the lower end of the latch bar 11 is disengaged from the corresponding door bar 12 and when the notches 22 are within the slot 10, the door 3 is free to move laterally. When any latch bar 11 is moved to unlatched position as aforesaid the arm 25 pivoted on the corresponding door is raised to engage the projection 27 within the notch 8 of the latch bar 29. Next, said operating bar 29 is moved longitudinally in a direction to move to open position the doors 3 which have their arms 25 engaged with the operating bar 29 as explained. So long as the bars 11 are in raised positions it is impossible for the projections 27 to become disengaged from the notches 28. When any door 3 is open it is impossible for its latch bar 11 to move downwardly because the lower end of said bar rests upon the upper surfaces of the door bar 12. Hence, it is impossible for any latch bar 11 to move downwardly to latched position unless the corresponding door 3 is in a position in which it is desired to latch it.

Throughout this specification and claims the word "wall" is used in its broad sense so as to include specifically the grating structure shown.

I am aware that the invention may be varied in construction, arrangement and relationship of parts without departure from the nature and principle thereof.

I do not restrict myself unessentially, but what I claim and desire to secure by Letters Patent is:—

1. The combination with an enclosing wall having a door opening, and a door slidable along said wall to close and to open said opening, of a bar mounted in said wall for vertical sliding movements, and means for actuating said bar to engage the upper and lower extremities of said door when said door is closed and thereby latch said door in closed position.

2. The combination with an enclosing wall having a door opening, and a door slidable along said wall to close and to open said opening, of a bar mounted in said wall for vertical sliding movements, means for actuating said bar to engage the upper and lower extremities of said door when said door is closed and thereby latch said door in closed position, and means for actuating said bar to disengage said door.

3. The combination with a wall having a door opening, means forming a concealing enclosure along said wall above said door opening, and a door slidable along said wall below said means to close and to open said opening, of a bar mounted in said wall for vertical sliding movements, and means within said enclosure for actuating said bar to engage the upper and lower extremities of said door when said door is closed and thereby latch said door in closed position.

4. The combination with a wall having a door opening, means forming a concealing enclosure along said wall above said door opening, and a door slidable along said wall below said means to close and to open said opening, of a bar mounted in said wall for vertical sliding movements to engage the upper and lower extremities of said door when said door is closed and thereby latch said door in closed position.

5. The combination with a wall having a door opening, means forming a concealing enclosure along said wall above said door opening, and a door slidable along said wall below said means to close and to open said opening, of a bar mounted in said wall for vertical sliding movements to engage the upper and lower extremities of said door when said door is closed and thereby latch said door in closed position, and means within said enclosure for disengaging said bar from the upper and lower extremities of said door.

6. The combination with a wall having a door opening, means forming a concealing enclosure along said wall above said door opening, and a door slidable along said wall below said means to close and to open said opening, of a bar mounted in said wall for vertical sliding movements to engage the upper and lower extremities of said door when said door is closed and thereby latch said door in closed position, means within said enclosure for disengaging said bar from the upper and lower extremities of said door, and means in connection with the door for preventing movement of said bar to latching position when said door is out of closed position.

7. The combination with a wall having a door opening, means forming a concealing enclosure above said opening and along said wall, and a door slidable along said wall to close and to open said opening, of a bar mounted for vertical movements to position to engage the upper extremities of said door when said door is closed and thereby latch said door in closed position, and means for concealing said bar from view and preventing access to said bar.

8. The combination with a wall having a door opening, means forming a concealing enclosure above said opening and along said wall, and a door slidable along said wall to close and to open said opening, of a bar

mounted for vertical movements to position to engage the upper extremities of said door when said door is closed and thereby latch said door in closed position, means for concealing said bar from view and preventing access to said bar, and means within said enclosure for moving said bar to position to unlatch said door.

9. The combination with a wall having a door opening, means forming a concealing enclosure above said opening and along said wall, and a door slidable along said wall to close and to open said opening, of a bar mounted for vertical movements to position to engage the upper extremities of said door when said door is closed and thereby latch said door in closed position, means for concealing said bar from view and preventing access to said bar, means within said enclosure for moving said bar to position to unlatch said door, and means within said enclosure for opening and closing said door.

10. The combination with a wall having a door opening, a concealing enclosure along said wall above said opening, a door slidable along said wall to close and to open said opening, and means within said enclosure for supporting said door, of a bar enclosed

within said wall and movable to engage the upper and lower extremities of said door to latch said door in closed position.

11. The combination with a wall having a door opening, a concealing enclosure along said wall above said opening, a door slidable along said wall to close and to open said opening, and means within said enclosure for supporting said door, of a bar enclosed within said wall and movable to engage the upper and lower extremities of said door to latch said door in closed position, and means enclosed within said enclosure for moving said bar to unlatching position.

12. The combination with a wall having a door opening, a concealing enclosure along said wall above said opening, a door slidable along said wall to close and to open said opening, and means within said enclosure for supporting said door, of a bar enclosed within said wall and movable to engage the upper and lower extremities of said door to latch said door in closed position, means enclosed within said enclosure for moving said bar to unlatching position, and means within said enclosure for opening and closing said door

MICHAEL J. TRACY.
